KEYBOARD MUSICAL INSTRUMENT WITH ELECTROMAGNETIC OPERATION.

Application filed September 26, 1928, Serial No. 663,806, and in France September 21, 1928.

The present invention relates to a keyboard musical instrument with electromagnetic operation, of the type having a branch circuit with a key lever controlling contacts for each note and a member interrupting the passage of the current through this part of the circuit at the desired frequency corresponding to this note.

In such musical instruments, it is known to employ tuning forks for interrupting the current at the desired frequency. It is also known to employ sound reproducing devices, such as telephones, megaphones or the like, as well as to employ resistances for regulating the intensity of the sound thus reproduced.

Our invention is characterized by the fact that the pulsations of current, produced by the operation of a key corresponding to one note, are sent simultaneously to one or more megaphones, telephones or the like, mounted in a part of the circuit common to a group of notes, and to an electromagnet special for each note and facing a suitably tuned magnetic vibrating sonorous body, such as a piano string.

By means of separate rheostats it is possible in the known manner to regulate separately, and as desired, the intensity of the sound produced by the megaphones, telephones or the like, and the intensity of the sound produced by the strings or other magnetic vibrating sonorous bodies, in such a way that the sound produced by one of these sonorous bodies, for example the megaphones or the like, can be added, with an intensity variable at will, to the sound produced by the other, for example the strings or the like, in the same group of notes or in several groups of notes.

The advantage of the arrangement forming the subject of the invention results from the following well known facts:

1. On the one hand, the setting in vibration of a piano string, by magnetic pulsations of the same rhythm as the vibration of the string, is easy to obtain for long strings giving deep notes; in this case the sound obtained is satisfactory, even if the synchronism of the two rhythms is imperfect. But the setting in vibration of the strings in the treble necessitates a perfection of synchronism that is very difficult to obtain in practice. The result in the treble is

therefore unsatisfactory and a great loss of intensity occurs as soon as there is a slight departure from synchronism.

2. On the other hand, the sounds produced by megaphones, telephones or the like are much more intense and musical in the higher notes than in the deeper ones.

It follows from the foregoing that by a suitable association of the two kinds of sound, it becomes possible to improve and to complete the results which each of the two methods is capable of producing separately.

In the drawings, Fig. 1 is an elevation of one form of construction of the arrangement according to our invention showing one group of notes of the instrument;

Fig. 2 is a plan view, seen from above, of the tuning fork and of the interrupting device which produces and controls the electromagnetic vibration of the tuning fork; and

Fig. 3 is a perspective view of the two pairs of contacts actuated by a key of the keyboard.

In Fig. 1, the tuning fork and the electromagnetic means sustaining the vibration thereof, are shown in full for one note and diagrammatically for the other notes.

Beneath each key D (Fig. 3) of the keyboard there are arranged two contacts namely, A, B, C, . . . and A¹, B¹, C¹, . . . adapted to cooperate with fixed contacts a, b, c, . . . and a¹, b¹, c¹, . . . respectively when the key is depressed. F designates a vibrating body adapted to interrupt the current at the frequency of the corresponding note. This vibrating body is shown as a tuning fork of which the vibrations are sustained electrically by the electro-magnet K. To each vibrator F there correspond two contact pieces E¹, E², making engagement with F at each vibration of the latter.

One of these contact pieces E¹ distributes the pulsations of current to one or more megaphones, telephones or the like H², mounted in a part of the circuit common to a group of notes. The other contact piece E² distributes the pulsations of current to an electromagnet L, special for each individual note and placed facing a magnetic vibrating sonorous body tuned in unison with the corresponding note, for example a piano string M. A rheostat R¹ is placed in series with the electromagnets L in a part of the circuit common to the group of notes

under consideration. R^2 is a rheostat placed in parallel to the megaphones H^2 or the like, in the part of the circuit common to the group of notes.

- 5 The electromagnet K, which actuates the tuning fork F, comprises two coils in series, (see upper part of Figs. 1 and 2). The contact piece E^1 is carried by a movable arm E^3 , secured to a shaft E^4 , journalled in two 10 bearings E^5 . This movable arm E^3 carries an iron blade E^6 , adapted to be attracted by the electro-magnet K; this attraction producing forced breaks of current between E^1 and F. A piston E^7 , immersed in a viscous 15 liquid E^8 contained in a vessel E^9 of a small sectional area, damps the oscillations of the movable arm E^3 . Due to this quick damping the tuning fork F soon becomes its own interrupting device.
- 20 The contact piece E^2 is also pivotally mounted (see upper part of Fig. 1); its inertia during the vibration of the tuning fork F producing making of contact followed by 25 breaking of contact of the same rhythm as the vibration of the tuning fork.

The mechanism operates in the manner which will now be described. When a key of the keyboard is pressed, it closes a contact such as A— a^1 and a second contact such 30 as A^1 — a^1 ; the current flows from the contact A— a to the vibrator F and there divides, one portion passing by the contact E^2 , which presses upon the vibrator F when the latter is at rest, traverses the electromagnet L and 35 the rheostat R^1 and returns to the source of current. The second portion of the current passes by the contact E^1 , which also presses upon the vibrator when the latter is at rest, traverses the electro-magnet K, then passes 40 the megaphones H^2 and the rheostat R^2 , and returns to the source. The passage of the current through the electro-magnet K starts the vibrator F in movement; and at this 45 moment, pulsations of current are sent by the contact E^1 to the megaphones H^2 and by the contact E^2 to the corresponding electromagnet L. The megaphones H^2 and the strings M sound simultaneously with intensities variable at will or separately, according 50 to the resistance given to the rheostats. Thus, when the resistance of the rheostat R^2 is nil, the strings M alone sound, for the megaphone or megaphones H^2 is or are short circuited; but if the resistance R^2 is not nil 55 and if the resistance R^1 is very great, or if the circuit is broken at R^1 , the megaphone or megaphones H^2 will alone sound.

It is thus possible, by suitable regulation 60 of the rheostats R^1 and R^2 corresponding to the different groups of notes, to cause in any one group of notes a predominance as desired of the sonorous bodies of one given type, either the telephones or megaphones or the like H^2 , or the piano strings M or the like, and at the same time it is possible to

cause a predominance in another group of notes of the sonorous bodies of different type.

What we claim is:

1. A keyboard musical instrument with 70 electromagnetic operation, comprising a circuit common to all the notes of the instrument and a key for each note, contacts actuated by said key, a branch circuit, an interrupter device controlled by said contacts and adapted to interrupt the flow of current in this branch circuit at the desired frequency corresponding to this note, a part of circuit common to a group of notes, sound reproducing devices mounted in said 80 common part of circuit, and a first contact member adapted to cooperate with the interrupter device in a part of each branch circuit corresponding to a note and to distribute pulsations of current to said sound 85 reproducing devices, together with a vibrating sonorous body tuned in unison with the corresponding note in a second part of each branch circuit, electromagnetic means for vibrating said sonorous body in said branch 90 circuit, and a second contact member adapted to cooperate with the interrupter device and to distribute pulsations of current to said electromagnetic means in each branch circuit, for the purpose described. 95

2. A keyboard musical instrument with electromagnetic operation, comprising a circuit common to all the notes of the instrument and a key for each note, contacts actuated by said key, a branch circuit, an interrupter device controlled by said contacts and adapted to interrupt the flow of current in this branch circuit at the desired frequency corresponding to this note, a part of circuit common to a group of notes, sound 100 reproducing devices mounted in said common part of circuit, and a first contact member adapted to cooperate with the interrupter device in a part of each branch circuit corresponding to a note and to distribute pulsations of current to said sound 105 reproducing devices, means in said common part of circuit for regulating the intensity of the sound produced by the said sound reproducing devices, together with a vibrating sonorous body tuned in unison with the corresponding note in a second part of each branch circuit, electromagnetic means for vibrating said sonorous body in said branch 110 circuit, and a second contact member adapted to cooperate with the interrupter device and to distribute pulsations of current to said electromagnetic means in each branch circuit, another part of circuit common to 115 the same group of notes, and means in said common part of circuit for regulating the intensity of the sound produced by the vibrating sonorous bodies corresponding to the notes of said group, for the purpose described. 120

125

3. A keyboard musical instrument with electromagnetic operation, comprising a circuit common to all the notes of the instrument and a key for each note, contacts actuated by said key, a branch circuit, a tuning fork controlled by said contacts and adapted to interrupt the flow of current in said branch circuit at the frequency corresponding to this note, an electromagnet for 10 vibrating said tuning fork, a part of circuit common to a group of notes, telephones mounted in said common part of circuit, a first contact member adapted to cooperate with the tuning fork in a part of each 15 branch circuit corresponding to a note and to distribute pulsations of current to said telephones, and a rheostat in said common part of circuit for regulating the intensity of the sound produced by the strings corresponding to the notes of said group; for the purpose described.

In testimony whereof we have signed our 35 names to this specification.

ALCIDE HECTOR MAITRE.

VICTOR HENRI GASTON MARTIN.
